Specification of Letters Patent.

Patented Oct. 1, 1912.

Application filed October 28, 1908. Serial No. 459,940.

To all whom it may concern:

Be it known that I, WILLIAM H. MUZZY, a citizen of the United States, residing at New York, in the county of New York and State 5 of New York, have invented certain new and useful Improvements in Adding-Machines, of which I declare the following to be a full, clear, and exact description.

This invention relates to improvements in 10 calculating or similar machines, and more particularly to the recording mechanism for same.

The principal object of this invention is to provide adjustable type carriers which may 15 be moved laterally so as to enable the printing of items in different vertical columns.

Another object is to provide a mechanism so that a part of the type carriers may be 20 independently adjusted, thereby enabling the listing of several items at a single operation of the machine.

Another object is to provide mechanism for disabling the transfer between sections 25 of the registering mechanism whenever the type carriers are separated.

With these and incidental objects in view, the invention consists in certain novel features of construction and combination of parts, the essential elements of which are set 30 forth in appended claims and a preferred form of embodiment of which is hereinafter described with reference to the drawings which accompany and form part of this specification.

Of said drawings: Figure 1 represents a side elevation partly broken away of the invention. Fig. 2 represents a partial top plan view of the driving clutch for the rotation shaft and the feeding devices for the 40 paper and ink ribbon. Fig. 3 represents a longitudinal section through the machine. Fig. 4 represents a detail perspective of the shifting levers for the type carriers. Fig. 5 represents a transverse section on the line 45 5-5 of Fig. 1. Fig. 6 represents a detail perspective of a part of the transfer disabling mechanism. Fig. 7 represents an enlarged longitudinal section through the registering mechanism. Fig. 8 represents a 50 partial side elevation with the operating handle and one of the side frames removed. Fig. 9 represents an enlarged longitudinal section through the recording mechanism.

Fig. 10 represents a detail perspective of one of the guide arms for the recording mechanism; and Fig. 11 represents a detail perspective, partly broken away of the two arms forming a printing hammer.

Described in general terms the machine comprises a plurality of banks of keys which determine the amount to be registered and recorded by the actuation of a main operating lever. The type carriers of the recording mechanism may be laterally shifted without disengaging them from their driving mechanism, so as to print in different columns upon a record sheet supported adjacent to said type carriers. The type carriers are arranged so as to be moved as a whole to enable the printing in columns at successive operations of the machine or in sections to allow the printing of separate columns during a single operation. Whenever the recording mechanism is split in sections, the transfer between the corresponding section of the registering mechanism is disabled.

Amount determining devices.—These devices comprise a plurality of banks of numerical keys 1, which, when depressed, act as stops for longitudinally movable bars 2, which are released upon the operation of the main operating lever 3, and are drawn forwardly by springs 4 connected at their ends to lugs 2^a projecting downwardly from bars 2, and to a suitable part of a casing 5 of the machine. The shanks 6 of the keys 1 are provided with cam slots 7, which terminate at their lower ends in horizontal slots 8. When the keys are depressed, the cam slots will engage with laterally projecting lugs 9, formed upon slides 10, (one for each bank of keys), and move the same forwardly. At its forward end each slide 10 has pivoted thereto a latching pawl 11, which, as the slide moves forwardly, engages with a cross rod 12, and thereby latches the operated keys of each bank in their depressed position and the inoperated keys in their elevated position by the lugs 9 formed upon the slides 10, passing in the horizontal grooves 8, formed in the key shank 6. The keys are released at the end of the operation of the operating lever 3 by suitable means which elevate the pawls 11 of the operated slides 10, thereby allowing the latter to be drawn to their nor-

mal position by spring 13, all of which is fully shown and described in the patent granted to W. F. Treadway, January 13, 1903, Number 718,176.

5 As the keys 1 are depressed, the slides 10 of the corresponding banks, when moved forward, will rock pawls 14 against the tension of springs 15, which connect the forward ends of said pawls with the latching pawls 11 and 10 raise the rearward ends 16 out of the path of ratchet teeth 17 formed upon the bars 2, so that, as the horizontal bar 18, which contacts with the lugs 2^a and holds said bars 2 rearward, is moved forward as hereinafter described, laterally projecting pins 19 on the bars 2, will contact with the depressed keys and thereby arrest the forward movement of said bars.

15 The main operating lever 3 is secured to 20 an outer end of a shaft 20, which has projecting upwardly therefrom an arm 21 (see Fig. 8), that is connected by a link 22 to a downwardly extending arm 23, secured at its upper end to a horizontal shaft 24. 25 Rigidly mounted upon the shaft 24 are two arms 25, provided with cam grooves 26, in which play rollers 27 extending laterally from arms 28 pivoted to brackets 29, secured to the rear end of the casing 5. The lower 30 end of each arm 28 has pivoted thereto a forwardly extending link 30 (see Figs. 5 and 8), which, at its forward end, is connected to an ear 31 projecting rearwardly from the cross bar 18.

35 It will be seen from the above description that when the operating handle 3 is pulled forward, the arm 21 will move in the same direction, and, by means of the link 22 and the arm 23, rock the shaft 24 downwardly 40 and forwardly. The cams 25 secured to the shaft 24 will rock in a similar direction, and move the transverse bar 18 forward through means of the levers 28 and links 30. The shaft 20 has centrally pivoted arms 20^a to 45 the ends of which are suitably secured the ends of coil springs 21^a and 22^a, which are put under tension by the forward movement of the operating lever 3, and which are used to return the parts to normal position. 50 A suitable dash pot may be used to retard a too rapid movement of the parts to normal position.

Recording mechanism.—Attached to the bars 2 (see Figs. 1, 3 and 5) are upwardly 55 extending arms 32, which have attached to their upper ends rack bars 33, which engage with pinions 34 upon opposite sides of casing 5. As shown in Figs. 1 and 5, the four right hand arms 32 extend diagonally through 60 openings 35 in the right hand frame of the casing 5, while the five remaining arms extend through similar openings upon the left hand side of the casing. The rack bars 33 carried by the four right hand arms 32 65 mesh with the pinions secured to the four

uppermost shafts 36, while the rack bars 33 located on the left hand side of the machine mesh with the pinions 34 secured to the lower five shafts 36. These shafts 36 are mounted in an arc of a circle struck from the center of a rotary shaft 37 suitably mounted in the casing 5.

70 Pinions 38 are mounted upon the shafts 35 within the side frames of the casing 5. These pinions, of which there is one for each shaft, are provided with feathers 39, which play in longitudinal grooves 40, formed in shafts 36. This construction permits the lateral movement of said pinions upon the shafts 36, and insures the rotation of said pinions with the shafts. These pinions 75 mesh with teeth 41, formed upon type carrier disks 42, which are loosely mounted upon the rotary shaft 37. Each of the disks 42 is provided with two segmental ribs 43 which act as guides for type blocks 44. 80 These blocks are provided with pins 45 which limit the inward movement of said blocks by contacting with the inner rib 43 and are held in this position by coil springs 46 which surround the stems 47 of the type blocks 44 and abut against the pins 45 and the outer rib 43. Each carrier 42 is provided with ten type blocks 44 with a zero type normally in printing position.

90 It will be seen from the above description that as the parts move forward, they will carry the arms 32 and the rack bars 33 with them and rotate the shafts 36 through means of the pinions 34 a corresponding 100 distance; the shafts 36, in turn, rotating the type carriers 42, so as to bring the proper type blocks 44 into printing position through means of the pinions 38 carried by the shafts 36. The mechanism for taking an impression 105 from the positioned type blocks will now be described.

Extending downwardly from the shaft 20, to which the operating lever 3 is secured, is an arm 48 which has secured to its lower end one end of a link 49, the other end of the latter being secured to the downward end of a lever 50, which is approximately centrally pivoted upon the casing 5 at 51, as shown in Fig. 1. The upper end of the lever 50 is formed into a segmental rack plate 52 which meshes with a pinion 53 loosely mounted upon the shaft 37. This pinion is provided with a collar 54 having two teeth 55 diametrically opposite each other (see Fig. 2), which are normally held in notches 56 formed upon a collar 57, secured to the shaft 37, by a coil spring 58 interposed between said pinion 53 and a collar 59 secured to the outer end of the shaft 37. As the operating lever 3 is pulled forward, the segmental rack plate 52 of the lever 50 will also be rocked forward through means of the link 49, thereby rotating the pinion 53 and collar 54 in the direction of the arrow (Figs. 130

1 and 2), and by means of the teeth 55, formed on said collar 54, rotating the shaft 37. As the operating lever 3 and the lever 50 are returned to normal position, the teeth 55 will be cammed out of the notches 56 in the collar 57 and rotate independently of the shaft 37. As it reaches its normal position, the teeth 55 of the collar 54 will be forced back into engagement with the notches 56 by the coil spring 58.

10 The shaft 37, as shown in Fig. 9, is provided with a longitudinal groove 60, into which enters splines 61 of cams 62 mounted upon the shaft 37, which construction allows 15 the cams to be moved laterally independently of the shaft 37, but compels the rotation of said cams with the shaft. Contacting with the periphery of the cams 62, are the ends of upwardly extending arms 63, 20 which form one part of a printing hammer for each type carrier 42. Each arm 63 is loosely mounted at its lower end upon a horizontal shaft 64 rigidly secured within the casing 5. Adjacent to each arm 63 is 25 an upwardly extending arm 65, which is slightly bent so that its upper end will be in position to contact with the stem 47 of the type block 44 that is in position to print. The arms 63 and 65 of each hammer are 30 provided with collars which have a recess 66 (see Figs. 9 and 11), which permit of a slight independent movement of the arms 65, so as to allow the latter to strike the stem 47 of the type block when the arm 63 is 35 suddenly arrested. This lost motion between said arms 63 and 65 is normally taken up by a light coil spring 67. The upper end of each arm 63 is held in contact with its respective cam 62 by a coil spring 68, 40 the ends of which are secured to the arm 63 and a collar suitably mounted upon the shaft 37.

It will be seen from the above description that as the operating lever 3 is pulled forward, the type blocks 44 mounted upon the type carriers 42 will take up positions corresponding to the keys depressed, and as said lever 3 completes its forward movement, the shaft 37, carrying the cams 62, 45 will have made a complete revolution, allowing the arms 63 to spring rearwardly until they will be suddenly arrested by the upper ends of said arms contacting with the low portion of the cams 62. This sudden 50 arresting of the arms 63 will allow the arms 65, through the recesses 66 to continue their rearward movements and force the positioned type blocks 44 to take an impression upon a record sheet 69 supported by a 55 platen roller 70, through an intervening ribbon 71.

Each pinion 38, mounted upon the shafts 36, is provided with a collar 72 that has an annular groove 73, into which plays prongs 60 74 of a bifurcated portion of an arm 75,

which is loosely mounted at its inner end upon the shaft 37. Loosely mounted upon the shaft 37 within the casing 5 and upon the outside of the type carriers 42, are bell cranks 76, one of which is also mounted between the fifth and sixth type carrier counting from the right (see Fig. 5). The ends of the horizontal arms of the bell cranks 76 are provided with handles 77, which have upwardly and downwardly extending arms 78 and 79 respectively, (see Figs. 1, 3, 4 and 9), the upwardly extending arms playing over an index 80 formed upon the casing 5, while the downwardly extending arms 79 are provided with plunger pins 81 which 80 engage in notches 82 to insure the proper alinement of the levers 76, and also to prevent accidental displacement thereof. The two end levers 76 are used for the displacement of all of the type carriers 42, while 85 the central lever 76 is used to displace only a part of said type carriers, so that a plurality of items may be entered in separate columns and readily distinguished upon the record sheet 69. A downwardly extending 90 arm of each of the bell crank levers 76 is guided by the horizontal rod 64.

It will be seen from the above that when all or part of the type carriers 42 are shifted laterally by the bell crank levers 76, their 95 companion pinions 78 and printing hammers will be carried therewith. The downwardly extending arms of the two outer bell crank levers 76 extend slightly below the horizontal shaft 64, and have fastened thereto plates 83 extending toward each other (see Figs. 5 and 6). When the type carriers are assembled so as to print as a whole, the plates 83 abut against each other, and an arm 84 carried by the left hand plate 83 100 (see Fig. 6), is cammed upwardly and held in this position by a pin 84^a against the tension of a coil spring 85, as shown in said figure. Whenever the type carriers are separated (as shown in Fig. 5) to print several 105 items during a single operation of the machine, the arm 84 carried by the plate 83 will be rocked downwardly by its spring 85 and disable the transfer mechanism between the fifth and sixth wheels of the register mechanism, as hereinafter described. The downward movement of the arm 84 is limited by a pin 86, around which the coil spring is wound.

The record sheet 69 (see Figs. 2, 3 and 9), is arranged to be fed forward one space upon each operation of the machine by the following described mechanism. Forming a part of the collar 59, secured to the outer end of shaft 37, is a cam disk 87, which engages with a pin 88 projecting from a plate 89, which is suitably guided upon the collar 59, and a shaft 90 upon which the platen 70 is rigidly secured. A ratchet wheel 91 is secured to the shaft 90 and is arranged to 115 120 125 130 135

be fed forward step by step by a pawl 92 carried by the plate 89, which is moved rearwardly upon each rotation of the shaft 37 by the cam disk 87, engaging with the pin 88. This plate 89 is returned to normal position by a light coil spring 93. On the opposite side of the plate 89 from the pawl 92, is mounted a similar pawl 94 which engages with a ratchet wheel 95 attached to a spool 96 around which the inking ribbon 71 is wound. This spool 96 is held in its adjusted position by leaf spring 97, one end of which is secured to one of the side frames of the casing 5, while its other end abuts 10 against the side of the ribbon spool, which is loosely mounted upon the shaft 90 and thereby frictionally holds said spool 96 in its adjusted position. The inking ribbon 71 passes from the spool 96 around a pin 98 extending from one of the side frames of the casing 5, and passes through a recess in said frame in front of the platen roller 70, the other end of said ribbon being wound around a similar spool 96 located upon the 25 opposite side of the machine. The latter spool is not provided with a ratchet wheel, but is frictionally held in place by a spring similar to the spring 97. Feed rollers (see Fig. 9), 99, 100 and 101 are located about 30 the platen roller 70 and between them the record sheet 69 is fed.

Registering mechanism.—The registering mechanism herein shown is somewhat similar to that shown in the patent granted to F. C. Rinsche, dated February 2, 1904, No. 751,207, and comprises a series of registering wheels 102, (see Figs. 3, 5 and 7), which are loosely mounted upon a horizontal shaft 103, suitably supported in the register casing. These wheels are provided with pinions 104, which are constantly in mesh with gear wheels 105 loosely mounted upon a horizontal shaft 106. The longitudinal movable bars 2 are provided with upwardly extending projections 107 to which are pivoted the forward ends of rack bars 108, which are arranged to move forwardly with said bars 2 and, at the end of their forward movement, to be thrown into engagement 45 with the gear wheels 105, so that as the said bars 2 are returned to normal position by the horizontal bar 18 abutting against the downward projections 2^a, they will turn the wheels 102 through means of the intermediate gear wheels 105 a distance corresponding to the forward movement of said bars 2. These rack bars 108 are thrown into engagement with the gears 105 at the extreme end of the forward movement of the 50 operating handle 3, at which time the bars 2 have taken up their proper position by the following means. The rock shaft 24 which is connected to the main rock shaft 20 by the previously described intervening mechanism (see Fig. 8), has fastened to it a down-

wardly extending arm 109, which carries at its lower end a roller 110, which at the end of the rocking movement of the shaft 24, contacts with the upper end of an upwardly extending arm 111 that is pivoted to a bracket 112 extending upwardly from the base of the machine, and rocks said arm 111 about its pivot. The upper end of the arm 111 is connected to the rearward end of a link 113, the forward end of which is connected to a lever 114, which at its lower end is fast to one end of a horizontal shaft 115, the latter being mounted in brackets 116 secured to the base of the machine. At the other end of the shaft 115 is secured a 80 similar lever 114, which is partially broken away in Fig. 8.

The upper end of the left hand lever 114 is provided with a segmental cam slot 117, while the right hand lever is only provided with a camming surface similar to the bottom of the slot 117, the purpose of which is to allow for the convenient assembling of the parts. Projecting into the slot 117 and resting upon the camming surface of the right hand lever 114 (see Figs. 3 and 5) are pins 118, which extend laterally from forwardly projecting arms 119 mounted upon a horizontal shaft 120, the latter being suitably mounted in the side frames of the casing 5. Connecting the forward ends of the arms 119 is a transverse rod 121, which plays in longitudinal slots 122 in the rearward ends of the rack bars 108.

It will be seen from the above description that at the extreme end of the forward movement of the operating handle 3, the roller 110 mounted upon the lower end of arm 109, secured to the rock shaft 24, will contact with the upper end of the arm 111 and by means of the link 113, rock the levers 114 forward, which movement will carry the rack bars 108 into engagement with the gear wheels 105 through means of the cam slot 117 and the camming surface of the levers 114 engaging with the pins 118, extending from the arms 119. At the extreme rearward movement of the operating handle 3, the arm 109, which moves in the same direction, will carry the roller 110 into contact with the upper end of an arm 123 suitably mounted at its lower end to a part of the casing 5 (see Fig. 8), and by means of a link 124, connecting the upper ends of the arms 123 and 111, rock the cam levers 114 rearwardly, and by the previously described intervening mechanism withdraw the racks 108 out of engagement with the gear wheels 105.

Transfer mechanism.—By reference to Fig. 7, it will be seen that the pinions 104, which are in mesh with the gears 105, are only one-third of the size of the latter, so that upon a third of a revolution of the gears 105, which is equivalent to a full revo-

lution of the registering wheels 102 and the pinions 104, the following described transfer mechanism will be set to add one upon the wheels 102 of the next higher denomination. Extending laterally from each of the gear wheels 105 are three pins 125, thus, as said wheel makes a third of a revolution, one of said pins 125 will contact with a nose 126 formed upon a lever 127 and elevate said lever slightly against the tension of its spring 128 so that a pin 129 projecting laterally from each of the levers 127 will raise a latching pawl 130 against the tension of its spring 131, the other end of the spring being connected to a rearwardly extending arm of a bell crank pawl 132, so that the vertical arm of said bell crank pawl 132 will pass under its latching pawl 130 and hold said pawl elevated while the lever 127 is returned to normal position. Each of the levers 127 and its companion pawl 130 are mounted upon a shaft 133 suitably mounted within the registering frame. Each of the bell crank pawls 132 is mounted upon a lever 134 which in turn is pivotally mounted upon a transverse shaft 135, the latter being mounted in the register frame. The movements of the pawls 132 are limited by pins 136 extending from the levers 134 into enlarged recesses in said pawls. Each of the levers 134 is provided with a transfer pawl 137 which engages teeth of the gear wheel 105 of the next higher denomination than that with which the lever 127 engages.

Upon a lever 134 which are connected to pins 139 projecting from the levers 134 and to fingers stamped from a sleeve 140 suitably mounted in the registering frame, pull the levers 134 forward to effect the transfer. The levers 134 are normally held in check by the bell crank pawls 132 engaging with the latching levers 130 and said levers are moved slightly rearward by mechanism hereinafter described, before the gear wheels 105 have started to rotate. On the left hand end of rock shaft 24 (see Fig. 8), is a segmental plate 141 provided with a cam slot 142 into which projects a pin 143 mounted in one end of a triangular shaped plate 144 which is pivoted at 145 upon the casing 5. Attached at 146 to the plate 144 is one end of a link 147, the forward end of which is connected to a lever 148 (see Fig. 7), which has a laterally extending rod 149 connected at its other end to a lever somewhat similar to lever 148, these levers 148 being mounted upon the shaft 135.

Upon the rocking of the shaft 24 by the operating lever 3, the segmental cam plate 141 will rock the triangular shaped plate 144 rearwardly, drawing the frame comprising the levers 148 and rod 149 rearwardly also by means of the link 147, thereby recocking

any of the transfer levers 134 that have been previously tripped, all of which is done before the registration is commenced. The levers 134 are drawn farther rearwardly by rod 149 than the position shown in Fig. 7, in which position they are held by fingers 150 projecting rearwardly from the sleeve 140 that are drawn into engagement with shoulders 151 formed upon the levers 134 by the springs 138. As the parts are returned to normal position a roller 152 carried by the upper end of the left hand lever 148 contacts with a finger 153, extending upwardly from the sleeve 140, and rocks the rearwardly extending fingers 150 of said sleeve out of engagement with the shoulders 151, and thereby allow any of the levers 134, whose companion latching pawls 130 have been previously tripped to be drawn forward by their springs 138 to effect the transfer, all of which is fully shown and described in the aforesaid patent to Rinsche.

Whenever it is desired to list a plurality of items during a single operation of the machine, the type carriers 42 are separated by the central bell crank lever 76, as previously described. When this is done it is also desirable to split the registering mechanism in sections, so as to accumulate separately the totals of the different groups of items listed. The splitting of the registering mechanism is accomplished by the cutting out of the transfer between the several sections, which is done in the following manner.

As the type carriers 42 are separated by the center bell crank 76, the plates 83 connected to the downwardly extending arms of the outer bell crank 76 are separated which allows the arm 84, carried by the left hand plate 83, to be rocked downwardly by its spring 85, carrying a foot 154 projecting from the arm 84, into contact with a transverse rod 155 supported by the rear ends of two arms 156 located upon opposite sides of the machine, the forward ends of which are secured to a shaft 157 mounted in the casing 5, and rock said shaft 157 and arms 156 rearwardly and downwardly against the tension of a coil spring 158, which keeps the rod 155 into contact with the foot 154 of the arm 84 (see Figs. 3, 7 and 9). Extending forwardly from the shaft 157 is an arm 159 with a hook projection 160, which, as said shaft 157 is rocked rearwardly, is carried into the path of a rearwardly projecting hook 161 of the transfer lever 134 for the sixth registering wheel 142, reading from the right of Fig. 5, so that as the transfer levers are carried rearwardly to the extreme position by the rod 149 (see Fig. 7), the hook projection 161 will pass slightly beyond the hook 160 and thereby hold this particular transfer 130

lever in its inoperative position until the type carriers are brought together by one of the outer bell crank levers 76. Owing to the friction between the hooks 160 and 161, caused by the strength of the spring 138 of the transfer lever 134 carrying the hook 161, the said lever is not released until the succeeding operation of the machine after the type carriers are brought together by the rod 149 contacting with the lever 134 and carrying it slightly farther rearwardly to relieve this friction, thereby allowing the spring 158 to return the arm 159 to a position out of the path of the hook 161 carried by the lever 134.

It will be seen that the machine shown has several possible modes of operation. It may be used as a single column adding machine, printing on the long narrow strip now in common use. It may also be used as a "wide carriage" machine, printing in any one of several lateral columns on a wide sheet of paper, serving thereby for many useful kinds of tabulation. Lastly it may be used as a so-called "split and normal" machine, printing and adding at once two separate columns, which columns may be adjacent or may be variably separated by any desired width of space within the limits of the machine. These various modes of operation enable the machine to perform functions and to achieve results entirely outside the scope of the single column machines now on the market. For instance, it is believed to be broadly novel to provide a construction in a "split and normal" machine permitting a variable separation through any desired width of space of the printed columns, and this function is of evident utility. The self contained printing device may also be noted as a distinct improvement in the art, especially in connection with the lateral adjustment of the printing elements. If the variable separation above referred to was desired in the prior machines, much difficulty would be experienced in shifting the hammers on account of the great space they occupy, which space would clearly have to be left vacant of other mechanism to permit such shifting. With the self contained structure this objection does not arise.

While the form of mechanism herein shown and described is admirably adapted to fulfil the objects primarily stated, it is to be understood that it is not intended to confine the invention to the one form of embodiment herein disclosed for it is susceptible of embodiment in various forms, all coming within the scope of the claims which follow.

What is claimed is:

1. In a machine of the class described, the combination with a plurality of type carriers, of an operating mechanism therefor, means for adjusting the type carriers inde-

pendent of movement of their operating mechanism, and relative to a record strip so as to print thereon in different columns, means for taking impressions from said type carriers and for feeding said record strip, and connections from said operating mechanism for actuating said impression taking and feeding means.

2. The combination with a recording mechanism, comprising a plurality of type carriers and operating mechanism therefor, of means for adjusting the type carriers independent of any movement of their operating mechanism and relative to a record strip so as to print thereon in different columns, and means adjustable with the type carriers for taking an impression therefrom.

3. The combination with a recording mechanism, comprising a plurality of type carriers and operating mechanism therefor, of means for adjusting the type carriers independent of any movement of their operating mechanism and relative to a record strip so as to print thereon in different columns, and hammers adjustable with said type carriers for taking an impression therefrom.

4. The combination with a recording mechanism, comprising a plurality of type carriers and operating mechanism therefor, of means for adjusting the type carriers independent of any movement of their operating mechanism and relative to a record strip, so as to print thereon in different columns, and hammers and operating devices therefor adjustable with said type carriers for taking an impression therefrom.

5. The combination with a recording mechanism, comprising a plurality of type carriers and operating mechanism therefor, of means for adjusting the type carriers independent of any movement of their operating mechanism and relative to a record strip so as to print thereon in different columns, and hammers and cams therefor adjustable with said type carriers for taking an impression therefrom.

6. The combination with a recording mechanism, comprising a plurality of type carriers and operating mechanism therefor, of means for adjusting the type carriers independent of any movement of their operating mechanism and relative to a record strip, so as to print thereon in different columns, and hammers for taking an impression from said type carriers.

7. The combination with a recording mechanism, comprising a plurality of type carriers and operating mechanism therefor, of means for adjusting the type carriers independent of any movement of their operating mechanism and relative to a record strip so as to print thereon in different columns, and pivoted hammers and operating devices therefor for taking an impression from said type carriers.

8. The combination with a recording mechanism, comprising a plurality of type carriers, of a shaft upon which the latter are mounted, means for adjusting the type carriers relative to a record so as to print thereon in different columns, and means controlled by the shaft for taking an impression from said type carriers.

9. The combination with a recording mechanism, comprising a plurality of type carriers, of a shaft upon which the latter are mounted, means for adjusting the type carriers relative to a record strip so as to print thereon in different columns, and piv-

10. 15. pivoted hammers controlled by the shaft for taking an impression from said type carriers.

10. The combination with a recording mechanism, comprising a plurality of type carriers, of a shaft upon which the latter are mounted, means for adjusting the type upon which the latter are mounted, means for adjusting the type carriers relative to a record strip, so as to print thereon in different col-

20. umns, pivoted type hammers for taking an impression from the type carriers, and cams mounted upon the shaft for operating the type hammers.

11. The combination with a recording mechanism, comprising a plurality of type carriers, of means for adjusting the latter relative to a record strip so as to print thereon in different columns, and two-part type hammers and operating devices therefor for

35. taking an impression from said type carriers.

12. The combination with a recording mechanism, comprising a plurality of type carriers, of means for adjusting the latter relative to a record strip so as to print thereon in different columns, and two-part type hammers and operating devices therefor adjustible with the type carriers for taking an impression therefrom.

45. 13. The combination with a recording mechanism, comprising a plurality of type carriers, of means for adjusting the latter relative to a record strip so as to print thereon in different columns, a shaft upon which the type carriers are mounted, and two-part type hammers controlled by the shaft for taking an impression from said type carriers.

14. The combination with a recording mechanism, comprising a plurality of type carriers, of means for adjusting the latter relative to a record strip so as to print thereon in different columns, a shaft upon which the type carriers are mounted, two-part type hammers for taking an impression from the type carriers, and cams mounted upon said shaft for operating the type hammers.

15. In a calculating machine, the combination with a recording mechanism, comprising a plurality of type carriers, of means

for adjusting the type carriers laterally so as to print upon a record strip in different columns, and laterally stationary means for controlling the type carriers in any of their laterally adjusted positions.

16. In a calculating machine, the combination with a recording mechanism, comprising a plurality of type carriers, of means for adjusting the type carriers laterally so as to print upon a record strip in different 75 columns, and a plurality of laterally stationary banks of keys for controlling the type carriers in any of their laterally ad-

justed positions.

17. In a calculating machine, the combination with a recording mechanism, comprising a plurality of type carriers, of means for adjusting the type carriers laterally so as to print upon a record strip in different 80 columns, means for taking an impression from the type carriers, and laterally stationary means for controlling the type carriers in any of their laterally adjusted positions.

18. In a calculating machine, the combination with a recording mechanism, comprising a plurality of type carriers, of means for adjusting the type carriers laterally so as to print upon a record strip in different 85 columns, means adjustable with the type carriers for taking an impression therefrom, and laterally stationary means for controlling the type carriers in any of their laterally adjusted positions.

19. In a recording mechanism, the combination with a type carrier, of means for supporting said carrier, and means controlled by said supporting means for taking an impression from the type carrier.

20. In a recording mechanism, the combination with a type carrier, of a supporting shaft therefor, and means controlled by the supporting shaft for taking an impression from said type carrier.

21. In a recording mechanism, the combination with a type carrier, of a supporting means therefor, means for taking an impression from said type carrier, and a cam carried by the supporting means for actuating the impression means.

22. In a recording mechanism, the combination with a type carrier, of a supporting means therefor, and a two-part hammer controlled by the supporting means for taking an impression from the type carrier.

23. In a recording mechanism, the combination with a type carrier, of an impression means therefor, and means for operating the impression means, the latter being in two parts with lost motion between same, so that when one part is suddenly arrested the other part will continue its movement to take an impression after which it is returned to normal position by a spring connecting the parts.

24. In a recording mechanism, the combination with a type carrier, of an impression means therefor, and a supporting shaft for the type carrier which controls the impression means, the latter being in two parts with lost motion between same, so that when one part is suddenly arrested, the other part will continue its movement to take an impression after which it is returned to normal position.

25. In a machine of the class described, the combination with a recording mechanism, of a registering mechanism, and a common means for splitting both of said mechanisms in sections to enable the recording and registering of a plurality of items during a single operation.

26. In a machine of the class described, the combination with a recording mechanism, of a registering mechanism, and means controlled by the former for splitting the latter in sections.

27. In a machine of the class described, the combination with a recording mechanism, of a registering mechanism, and means controlled by one of said mechanisms for splitting the other in sections.

28. In a machine of the class described, the combination with a recording mechanism including a plurality of type carriers, of means for splitting said mechanism in sections by shifting a part of said carriers, a registering mechanism, and means controlled by the shifting means for splitting the registering mechanism in sections.

29. In a machine of the class described, the combination with a recording mechanism including a plurality of type carriers, of means for splitting said mechanism in sections, by shifting a part of said carriers, a registering mechanism including a plurality of wheels and transfer devices between same, and means controlled by the shifting means for splitting the registering mechanism in sections by disabling a part of the transfer devices.

30. In a machine of the class described, the combination with a recording mechanism, of a registering mechanism including a plurality of wheels and transfer devices between same, and means controlled by the recording mechanism for splitting the registering mechanism in sections by disabling a part of the transfer devices.

31. In a machine of the class described, the combination with a plurality of type carriers arranged to be shifted laterally as a whole or in sections, of a registering mechanism arranged to be operated as a whole or in sections, and means for splitting the registering mechanism in sections when a part of the type carriers are shifted, but which is inoperative when the type carriers are shifted as a whole.

32. In a machine of the class described,

the combination with a plurality of type carriers arranged to be shifted laterally as a whole or in sections, of a registering mechanism including wheels and transfer devices between same, arranged to be operated as a whole or in sections, and means for splitting the registering mechanism in sections by disabling a part of the transfer devices when a part of the type carriers are shifted, but which is inoperative when the type carriers are shifted as a whole.

33. In a machine of the class described, the combination with a totalizer and recording devices, of an operating mechanism for inserting items in said totalizer and for also positioning the recording devices, means for producing relative lateral adjustment between said recording devices and a record material, whereby a record may be made in any of a plurality of columns, and means for giving a variable separation between parts of said recording devices.

34. In a machine of the class described, the combination with a totalizer and recording devices, of an operating mechanism for inserting items in said totalizer and for also positioning said recording devices, and means for producing a variable lateral separation between parts of said recording devices.

35. The combination with a recording mechanism, comprising a plurality of type carriers and impression means therefor, operating mechanisms for said type carriers and said impression means, and means for adjusting the type carriers and the impression means independent of any movement of their operating mechanisms and relative to a record strip, so as to print thereon in different columns.

36. In a recording mechanism, the combination with a type carrier, of means for supporting said carrier, means controlled by said supporting means for taking an impression from the type carrier, and means for adjusting said type carrier and impression means independent of any movement of said supporting means and relative to a record strip, so as to print thereon in different columns.

37. In a recording mechanism, the combination with a type carrier, of a supporting means therefor, means for taking an impression from said type carrier, means carried and controlled by said supporting means for actuating the impression means, and means for adjusting the type carrier, impression and actuating means independent of any movement of the supporting means and relative to a record strip, so as to print thereon in different columns.

38. In a machine of the class described, the combination with a printing mechanism comprising a plurality of type carriers, of means for differentially positioning said

type carriers, and means for producing a variable lateral separation between certain of said type carriers.

39. In a machine of the class described, the combination with a printing mechanism comprising a plurality of type carriers, of means for differentially positioning said type carriers, devices for producing lateral movement of said type carriers past a record material, said devices being constructed to permit a variable lateral separation between certain of said type carriers.

40. In an accounting machine, the combination with a plurality of type carriers for recording items and the total thereof, of a totalizer for accumulating the total of the items recorded, means for separating the type carriers so as to record a plurality of items in separate columns simultaneously and means, operating as an accompaniment to the separation of the type carriers, for splitting the totalizer so as to accumulate

separately the totals of the columnated items.

41. In an accounting machine, the combination with a plurality of type carriers for recording items and the total thereof, of a totalizer including transfer devices for accumulating the total of the items recorded, means for separating the type carriers so as to record a plurality of items in separate columns simultaneously, and means, operating as an accompaniment to the separation of the type carriers, for disabling a portion of the transfer devices for the purpose of separately accumulating the totals of the columnated items.

In testimony whereof I affix my signature in the presence of two witnesses.

WILLIAM H. MUZZY.

Witnesses:

C. A. HEIBIG, Jr.,
CARL W. BENST.

Correction in Letters Patent No. 1,039,783.

It is hereby certified that in Letters Patent No. 1,039,783, granted October 1, 1912, upon the application of William H. Muzzy, of New York, N. Y., for an improvement in "Adding-Machines," an error appears in the printed specification requiring correction as follows: Page 7, lines 21-22, strike out the words "means for adjusting the type upon which the latter are mounted"; and that the said Letters Patent should be read with this correction therein that the same may conform to the record of the case in the Patent Office.

Signed and sealed this 29th day of October, A. D., 1912.

[SEAL.]

C. C. BILLINGS,
Acting Commissioner of Patents.
